UNITED STATES PATENT OFFICE.

WASYL HUCAL, OF CHICAGO, ILLINOIS.

DESIGN FOR A COMBINED LAMP AND TALKING-MACHINE CASING.

57,911.

Specification for Design.

Patented May 17, 1921.

Application filed January 31, 1921. Serial No. 441,489. Term of patent 14 years.

To all whom it may concern:

Be it known that I, WASYL HUCAL, a citizen of Austria, formerly residing in the Province of Galicia, and now residing at Chicago, county of Cook, and State of Illinois, have invented a new, original, and ornamental Design for a Combined Lamp and Talking-Machine Casing, of which the following in a specification, reference being

had to the accompanying drawing, forming a part hereof.

The figure is a view in front elevation of a combined lamp and talking machine casing.

I claim:

The ornamental design for a combined lamp and talking machine casing, as shown.

WASYL HUCAL.
